IGNITION SYSTEM

Theodore B. Holliday and Clarence S. Irvine,
Dayton, OhioOriginal application February 28, 1939, Serial No.
259,001. Divided and this application November
17, 1939, Serial No. 304,962

6 Claims. (Cl. 123—148)

(Granted under the act of March 3, 1883, as
amended April 30, 1928; 370 O. G. 757)

The invention described herein may be manufactured and used by or for the Government for governmental purposes, without the payment to us of any royalty thereon.

5 This invention relates to ignition systems for internal combustion engines and more particularly to an ignition system having a transformer associated with each of the cylinders of the engine and a device for checking or testing the operation of the engine, this application being a division of our co-pending application Serial No. 259,001.

10 An object of this invention is to provide an ignition system that utilizes one or more transformers or induction coils for each of the cylinders.

15 Another object of this invention is to provide an ignition system wherein the distributor is located in the low tension side of the electrical circuit.

20 Another object of this invention is to provide an ignition system for an internal combustion engine and the like, which ignition system may be tested for defects by merely manipulating the ignition system itself.

25 Another object of this invention is to provide an ignition system for a multi-cylinder internal combustion engine wherein the circuit is closed for a sufficient period of time through each transformer to permit a sufficient voltage impulse to be generated to cause a spark of sufficient duration to discharge the fuel charge within the cylinder.

30 Another object of this invention is to provide an auxiliary test circuit for an ignition system for an internal combustion engine, whereby the defective cylinder may be located while the engine is operating and the circuit leading to the defective cylinder may be tested while the engine is inoperative.

35 Other objects and advantages reside in the construction of parts, the combination thereof and the mode of operation, as will become more apparent from the following description.

40 45 In the drawing, Fig. 1 discloses a schematic wiring diagram of the preferred embodiment of the ignition system.

Fig. 2 discloses a schematic circuit wiring diagram of the preferred modification.

50 In the past, various attempts have been made to provide a test apparatus for detecting the inoperative cylinder while the engine is running. Two systems have been utilized for making this test. The one method is to shunt the spark gap of each cylinder, so as to ascertain whether or not

shunting the spark gap causes additional cylinders to misfire. The other method is to open-circuit the high tension circuit leading to one or more cylinders, so as to determine in this manner which one of the cylinders is misfiring. These tests have all been made in the high tension portion of the circuit. Due to the fact that it is very desirable to use as short leads as possible and as few leads as possible in the high tension circuit, these methods of testing the circuit have been found unsatisfactory, especially in aircraft engines. The corona loss in the high tension circuit is substantially directly proportional to the length of the high tension voltage leads. Usually, there are excessive corona losses in the high tension side of the distributing harness.

In the conventional ignition systems now on the market, the distributor is in the secondary circuit of the ignition system. The construction of a distributor for high voltage is not a simple matter and considerable trouble is experienced with burning of the insulating rotor. This burning of insulation results in charred portions becoming a good conductor of high voltage energy and thereby decreases the voltage impulse that is 25 available for each spark plug. Furthermore, the high voltage wiring, although heavily insulated, is susceptible to the effects of atmospheric moisture and high engine temperatures. These troubles are aggravated by the necessity of locating the high tension cables around and between the cylinders. Due to the heat generated by the cylinders, the insulating material has a tendency to fail, become carbonized and lose its properties as an insulating material. 30 35

In commercial aircraft the magneto, even though a dual ignition system is used, is still a single source of electrical energy. This is due to the fact that only one drive from the engine is used. In addition thereto, the operation of either 40 half of a dual ignition system is dependent upon one high voltage coil in the magneto. Failure of this coil will cause inoperation of one spark plug in each cylinder. When magnetos are used, there is some difficulty in timing the magnetos, especially when used in connection with radial engines. Although the cylinders are equally spaced around the crankcase, the timing of the several cylinders cannot be equally spaced, because a common master rod is used. The deviation from equal timing may be as high as nine degrees (9°) in seven (7) cylinder engines. This matter can be corrected by using a multi-lobe cam with the magneto. These lobes would be so located on the cam that the timing is always 45 50

correct; but this solution is rather expensive, complicated, and conducive to trouble.

It is the purpose of the present invention to overcome the above objections and to produce a more simple and a less critical assembly. The principle is to conduct direct current to the primary of a transformer or induction coil which is located on or near each cylinder. The secondary winding of this transformer will develop a spark when the primary circuit is interrupted, causing a rapid change in the magnetic field of this secondary winding, resulting in a voltage impulse being generated which is proportional to the change in flux.

By properly designing the primary winding and the secondary winding of each transformer, a satisfactory voltage impulse may be produced in the secondary winding by merely utilizing the storage battery voltage or the voltage generated by the conventional generator charging the storage battery. Thus, it is seen that by this system, two sources of electrical energy are available, one from the battery and the other from the generator, so that in the event one fails, the other may be tapped or utilized. Furthermore, by utilizing a transformer which may have two primary windings and two secondary windings, if dual spark plugs are in association with each cylinder, the failure of one coil or several coils will not result in half or all of the electrical system becoming inoperative. Furthermore, by utilizing transformers adjacent each cylinder or mounted on each cylinder, the high tension leads can be extremely short, thereby reducing corona losses to a minimum.

By utilizing a transformer for each cylinder, the distributor is located in the low tension or primary circuit. This has numerous advantages in that it greatly reduces the hazard caused by high voltage used in the secondary. Furthermore, the distributor may be placed at any convenient location and low tension leads extending from the distributor to the primary terminals of the transformer located at or near the cylinders. The low tension leads, although quite long, do not result in serious corona losses or current leakage, due to the low potential used in the primary circuit. This circuit arrangement permits the use of an auxiliary circuit in the low tension circuit of the ignition system, which auxiliary circuit may be utilized first, to test for the misfiring cylinder during operation of the motor, and second, the testing of the circuit leading to the misfiring cylinder when the motor is inoperative.

This has been accomplished by providing a series of shunt circuits that may be connected across the terminals of the distributor, so as to continuously energize the primary winding of any one transformer, thereby interrupting any periodic flow of current or voltage impulses in the secondary circuit. If, for example, a shunt is connected across the distributor so as to shunt the circuit leading to cylinder number three, there will be no spark in this cylinder. If this is the defective cylinder, the motor will continue to operate as before. Thus, the misfiring cylinder is found. If this cylinder is not misfiring prior to the test, it will aggravate the operation of the motor, that is, it will cause another cylinder to misfire, thereby indicating that the cylinder under observation is normally functioning. This may be done while the airplane is in flight, or it may be done while testing the engine at the hangar. The switches are preferably located so as to be available to the pilot or the mechanic

on board ship, as the case may be. This circuit may further be utilized in testing the engine while it is inoperative, that is, while it is standing still.

Referring to the drawing, the reference character 10 designates a generator having one terminal grounded and the other terminal connected to an ignition switch 12. This ignition switch 12 is connected through a suitable lead 14 to a contact arm 16 in the distributor 18. This contact arm 16, shown schematically in Figures 1 and 2, is driven in synchronism from the engine.

The distributor has a plurality of stationary contacts 20a, 20b, 20c, 20d, 20e and 20f, there being one stationary contact for each cylinder. The distributor is located in the low tension side, or in the primary circuit of the ignition system, thereby low voltages are used. Being the circuits from the contacts of the distributor are all identical excepting for the length of the leads, et cetera, only one of these circuits has been shown and described.

The fixed terminal or contact 20a in the distributor is connected to one terminal of each of the primary windings 22 and 24, having the other terminal of each winding connected to a busbar 25 which is grounded through a switch 26 or a switch 28, as the case may be. The primary winding 22 links a secondary winding 30, having one terminal grounded at 30a and the other terminal connected to one terminal of a spark gap 34, the other terminal of the spark gap being grounded at 36. This spark gap is the usual spark gap found in conventional spark plugs. The winding 24 links a secondary winding 32, having one terminal grounded at 30a and the other terminal connected to one terminal of a spark gap 38, having the other terminal of the spark gap grounded at 40. By this arrangement a dual ignition system is provided for each cylinder, this is, the spark gap 34 and the spark gap 38 are preferably located within the same cylinder, so that in the event one of the transformers has failed or one of the spark plugs fails, the other transformer and the other spark plug will continue to function.

The switches 26 and 28 are always closed under normal operating conditions. The other contacts of the distributor are connected to like transformers, one pair of transformers for each of the other cylinders and each of the other contacts of the distributor. If a cylinder is found to misfire, it is rather difficult to locate the cylinder, especially in the event a great number of cylinders are used, as for example in a 24 cylinder engine.

In the embodiment disclosed in Figure 1, the transformers of a particular cylinder may be made inoperative by an auxiliary test circuit which will now be described. The contact 20a is connected through a lead 50 to a switch 52 connected by a lead 54 to the lead 14. By closing the switch 52, current is at all times supplied to the windings 22 and 24. It is a well known electrical phenomenon that a current continuously flowing through a winding will result in a zero current flow in and a zero voltage output from the secondary windings of the transformer, as the E. M. F. generated in the secondary winding of the transformer is proportional to the rate of change of the magnetic flux linking the secondary winding. A continuously flowing current in a primary winding results in no change of flux in the secondary winding. By this system any one of the transformers may have the ignition system in-

10 interrupted by closing the switch corresponding to the transformer in the auxiliary circuits, that is, the switch 52a for the transformer shown, 52b for the transformer connected to the contact 20b of the distributor, et cetera. When the misfiring cylinder is located, the engine may be stopped and the same circuit utilized for testing the functioning of the ignition system for the particular cylinder that is misfiring. First, instead of supplying electrical energy from the generator 10 which is now standing still, the battery 56 is connected through the ignition switch 12 to the lead 14. Assuming for the sake of argument that the ignition system shown schematically is interconnected to the particular cylinder that has been misfiring, by measuring the voltage impulses across the spark gap 34 or across the spark gap 38 when the switch 52a is intermittently opened and closed, it may be determined whether or not the 20 circuit is defective. If a sufficient voltage impulse is generated across the spark gaps, it is reasonable to assume that the defect lies either in the distributor per se or some mechanical portion of the engine other than the ignition system.

25 The circuit shown in Figure 1 in addition to testing the ignition system so as to locate the misfiring cylinder, may also be utilized to check the transformers to determine whether or not one or more transformers may be burned out or one or more spark plugs may be defective or for some reason one or more of the parallel circuits is inoperative. This test may be performed while the engine is operating. By referring to Figure 1 it can readily be seen that one terminal of each 30 transformer having the primary winding 22 is connected to the bus-bar 25. By merely opening the switch 26, all of the primary windings 22 are open-circuited, so that no current flows through these windings. The charges in the 35 cylinders are then ignited by the spark gap 38 in series with the secondary winding 32 linking the primary winding 24. If one or more of the transformers having the primary windings 24 are defective, or if one or more of the spark 40 plugs associated with the spark gap 38 are defective, such defect will result in a misfiring cylinder or misfiring cylinders when the switch 26 is open. If one or more cylinders misfire, the particular cylinder may be located by closing in turn 45 the switch 52a, 52b, 52c, et cetera, so as to determine which cylinder is misfiring.

50 After the transformers having the primary windings 24 have been tested, the switch 26 may be closed and the switch 28 opened. One terminal of each transformer having the primary winding 24 is connected to the bus-bar 25. By opening the switch 28, tests may be made to ascertain whether or not any of the circuits including the primary windings 22 and the secondary windings 30 are defective. If they are, they may be located 55 as described above.

60 This test has been described as being made while the engine is operating. A similar test may be conducted while the engine is standing still by merely measuring the voltage impulses across the several spark gaps.

65 In the modification disclosed in Figure 2, another circuit arrangement has been shown for testing the ignition system to ascertain which 70 cylinder may be misfiring. In this circuit the distributor 10 is connected through an ignition switch 60 having one terminal connected to a rotary contact 62, shown schematically, arranged to contact in seriatim the contacts 64a, 64b, 64c, 64d, 75 64e, and 64f of the distributor 66. The terminals

64a, b, c, d, e, and f are connected to their respective transformers, of which one has been shown, which transformers are identical to those described in connection with the modification disclosed in Figure 1. One primary terminal of the winding 22 and one primary terminal of the winding 24 are connected to ground through switches 70a, 72a, 74 and 76, for the particular transformer shown. The other transformers are connected to ground through switches 70b, 72b, 10 70c, 72c, et cetera, and finally, the switches 74 and 76. It is to be noted that one transformer associated with each cylinder is connected through the switch 74 to ground and the other transformer for each cylinder is connected through the switch 76 to ground. In normal operation all of the switches are closed.

Two tests may be made by this circuit arrangement. By opening switch 74, only one spark plug 20 will be energized for each cylinder, assuming that all of the transformer windings associated therewith are functioning properly. When the switch 74 is opened, the transformer windings 22 and 30 will energize the spark gap 34 in each of the cylinders. If all of the cylinders continue to fire with the switch 74 open, it is evidence that all of the windings 22 and 30 are functioning and all of the spark plugs 34 are functioning. If it develops that one of the cylinders is misfiring; or more of the cylinders are misfiring, the missing cylinder 25 may be located by opening in turn switches 70a, 70b, 70c, et cetera, to thereby locate the missing cylinder. If, for example, cylinder number four is missing, as evidenced by opening the switch 70d, then the trouble may be located. After the missing cylinder has been located, this portion of the ignition circuit effecting this particular cylinder may then be inspected to determine the cause 30 of the trouble. By closing switch 74 and opening switch 76, it may be determined whether or not all of the primary windings 24, secondary windings 32 and the spark plugs forming the spark gaps 38 are functioning. If, for example, it is found that the third cylinder is now missing, this 35 portion of the system may be further inspected.

40 By this circuit arrangement it is possible to locate defects in the ignition circuit prior to the misfiring of the cylinder, as one of the spark plugs for the cylinder may be functioning properly 45 without any spark across the other spark plugs. The circuit disclosed in Figure 2 permits testing of the ignition system to locate a defect before it 50 may result in a failure of the engine to operate properly.

55 "A group of transformers," as used in the claims is, used to designate the transformers having the windings 22 and 30, one for each cylinder, and "another group" refers to the transformers having the windings 24 and 32, that is, one transformer for each cylinder. It can be readily seen that there are two groups of transformers, each group having one transformer for each cylinder. "Cutting out the transformer" or similar terminology used in the claims, is used to designate the 60 open-circuiting or the shunting of any of the windings, or otherwise causing the transformer to fail to supply a voltage impulse to the spark plug.

65 It will be understood that within the purview of 70 this invention various changes may be made in the form, details, proportion and arrangement of parts which generally stated consist in a system capable of carrying out the objects set forth, in the novel parts, combination of parts and mode 75

of operation, as disclosed and defined in the appended claims.

Having thus described our invention, we claim:

5. In a dual ignition system for an internal combustion engine having a source of electrical energy, a distributor connected to the source of energy, said distributor having a plurality of outlet contacts one for each of the cylinders in the engine, the combination including two groups of 10 transformers, each group having one transformer for each cylinder, the primary windings of the transformers for each cylinder being connected to the outlet contacts of the distributor, a pair of bus-bars, a switch for connecting each bus-bar to ground, the other terminal of the primary winding of each transformer in one group being connected to one bus-bar, the primary windings of the transformers in the other group being connected to the other bus-bar, so that the primary 15 windings of one group may be opened by opening the switch between the bus-bar and ground so as to cause the engine to operate on the portion of the ignition system including the other group of 20 transformers, and a pair of spark plugs for each cylinder energized cyclically from the secondary of the transformers.
2. In a dual ignition system for an internal combustion engine having a source of energy, a distributor connected to the source of energy, 30 said distributor having a plurality of outlet contacts one for each of the cylinders in the combustion engine, the combination including two groups of spark plugs, two groups of transformers, each group including one transformer for each cylinder, means for interconnecting the primary windings of the transformers to the outlet contacts, means for connecting the secondary windings to each a spark plug, one set of windings of each group having one terminal grounded, and a pair of bus-bars connected to ground through each a switch, the other set of 35 windings of one group having one terminal connected to one of said bus-bars, the corresponding set of windings of the other group having one terminal connected to the other bus-bar, the opening of one switch disconnecting one group of 40 transformers to ground causing the other group of transformers to cyclically energize the spark plugs within the engine.
4. In a dual ignition system for an internal combustion engine having a pair of spark plugs for each cylinder energized from a source of electrical energy through a distributor, the combination including two groups of transformers, each group including one transformer for each cylinder, one terminal of each of the primary windings being connected to the distributor, means for connecting one terminal of each secondary winding to its spark plug, one set of windings of each group having the other terminal grounded, a pair of bus-bars connected to ground each through a switch, the other set of 45 windings of one group having one terminal connected to one of said bus-bars, the corresponding set of windings of the other group having one terminal connected to the other bus-bar, the opening of one switch disconnecting one group of 50 transformers to ground causing the other group of transformers to cyclically energize the spark plugs within the engine, and auxiliary testing means including shunt circuits connected across the distributor for supplying a continuous current to the portion of the circuit under test.
5. In a dual ignition system for an internal combustion engine having a pair of spark plugs for each cylinder energized from a source of 55 electrical energy through a distributor, the combination including two groups of transformers, each group including one transformer for each cylinder, one terminal of each of the primary windings being connected to the distributor, means for connecting one terminal of each secondary winding to its spark plug, one set of windings of each group having the other terminal grounded, a pair of bus-bars connected to ground each through a switch, the other set of 60 windings of one group having one terminal connected to one of said bus-bars, the corresponding set of windings of the other group having one terminal connected to the other bus-bar, the opening of one switch disconnecting one group of 65 transformers to ground causing the other group of transformers to cyclically energize the spark plugs within the engine, and switching means including one switch in one of the windings of each of the transformers to open-circuit a transformer in the other group.
6. In a dual ignition system for multi-cylinder internal combustion engines having a source of electrical energy connected to a distributor having a plurality of outlet contacts energized cyclically from a source of electrical energy, the combination including two spark plugs for each cylinder, two groups of transformers, each group including one transformer for each cylinder, the primary windings being connected to the outlet contacts in the distributor, the secondary windings being connected to the spark plugs of the engine so as to electrically energize the cylinders in parallel, means for cutting out one group of transformers, and means for cutting out any one transformer of the other group of 70 transformers.
